DESIGN FOR A RING-LOOP TOY

David Davidson, Los Angeles, Calif.

Application February 15, 1945, Serial No. 117,964

Term of patent 3½ years

(Cl. D34—15)

To all whom it may concern:

Be it known that I, David Davidson, residing at Los Angeles, in the county of Los Angeles and State of California, have invented a new, original, and ornamental Design for a Ring-Loop Toy, of which the following is a specification, reference being had to the accompanying drawing, forming a part thereof.

Figure 1 is a perspective view of ring-loop toy showing my new design; and

Figure 2 is a side elevational view thereof.

I claim:

The ornamental design for a ring-loop toy, as shown.

DAVID DAVIDSON.
